ABSTRACT

In a toe piece of a safety ski binding wherein the toe of the soleplate of the skier's boot is releasably clamped by a clamping member, there are provided a base plate having two spaced apart pins near the fore end and the rear end thereof respectively, a body pivotally mounted on the first pin located near the fore end and formed with a cam receiving chamber near the rear end thereof, a cam slidably received in the cam receiving chamber, a cam surface in the form of an arcuate recess formed at the center of the rear end surface of the cam, a compression spring contained in the body in the axial direction thereof for normally urging the cam surface against the second pin located near the rear end of the base plate, means for adjusting the spring, and a toe clamping member secured to the body at the end thereof whereby when a transverse force exceeding a predetermined safety limit preset by the spring is applied to the boot, the second pin is caused to be disengaged from the cam surface to allow the cam and the body to rotate about the first pin located near the fore end of the base plate thereby releasing the toe from the toe clamping member.

TOE PIECES OF SAFETY SKI BINDINGS

BACKGROUND OF THE INVENTION

This invention relates to a safety ski binding and, more particularly, to a toe piece for releasably holding the toe of the soleplate of a ski boot.

The safety ski binding usually comprises a toe piece for holding the toe of the soleplate and quickly releases the toe whenever a transverse load applied to the boot exceeds a predetermined safety limit or a permissible maximum load which may cause a serious injury to the skier such as a bone fracture, and a heel piece adapted to engage the rear end of the soleplate for applying thereto a forward pressure.

A prior art toe piece comprises a base plate secured to the ski, a body pivotally mounted on the base plate so as to rotate about a pivot pin when the transverse force applied to the boot exceeds the safety limit and a toe clamping piece pivotally mounted on another pivot pin so as to releasably engage the toe of the soleplate by the cooperation of a resilient latching force applied by the body and the forward pressure applied by the heel piece, thereby resiliently absorbing the shocks applied to the boot during normal operation of the ski.

Since the ski binding is used under low temperature environments, it often becomes inoperable due to deposition of snow or ice. The construction described above is not desirable because it includes two pivot pins. Moreover, the toe piece of such construction requires a large number of component parts and hence is complicated in construction and expensive.

SUMMARY OF THE INVENTION

Accordingly, it is an object of this invention to provide a novel toe piece of an improved construction that requires only a single pivot pin.

A further object of this invention is to provide an improved toe piece requiring a relatively small number of component parts and can be readily fabricated into a rugged and simple construction.

Still further object of this invention is to provide an improved toe piece utilizing a cam made of a synthetic resinous material having self lubricating property thereby assuring a positive operation of the toe piece under an extremely low temperature environment.

According to this invention, these and further objects can be accomplished by providing a toe piece of a safety ski binding of the type including a rotatable toe clamping member which acts to normally clamp the toe of the soleplate of a ski boot but is rotated to release the toe when a transverse force exceeding a predetermined limit is applied to the boot, characterized in that the toe piece comprises a base plate to be secured to the ski, first and second pins which are secured to the base plate near the fore end and the rear end thereof respectively, a body pivotally mounted on the first pin located near the fore end, the body being provided with a cam receiving chamber near the rear end thereof, a cam received in the cam receiving chamber to be slideable in the longitudinal direction of the axis of the ski, the rear end surface of the cam being provided with a recessed cam surface engageable with said second pin near the rear end of said base plate, a compression spring contained in the body in the axial direction thereof for normally urging the recessed cam surface against the second pin, means for adjusting the force of the spring, and a toe clamping member secured to the

body at the rear end thereof, whereby when a transverse force exceeding a predetermined safety limit preset by the spring is applied to the boot, the second pin is caused to be disengaged from the cam surface to allow the cam and the body to rotate about the first pin thereby releasing the toe from the toe clamping member.

The toe clamping member has a cup shaped configuration and comprises a single or two members connected to the body by means of a bolt or bolts which is used to adjust the vertical position of the toe clamping member.

The cam is preferably made of a self lubricating substance such as tetrafluoroethylene.

BRIEF DESCRIPTION OF THE DRAWINGS

In the accompanying drawings:

FIG. 1 is a top plan view, with the cover plate removed, of one embodiment of the toe piece embodying the invention;

FIG. 2 shows a longitudinal sectional view of the toe piece shown in FIG. 1 taken along a line II — II;

FIG. 3 is a bottom plan view of the body used in the toe piece shown in FIGS. 1 and 2;

FIG. 4 is a top plan view of the body;

FIG. 5 is a rear end view of the body;

FIG. 6 is a perspective view of the essential component elements of the toe pieces shown in FIGS. 1 and 2;

FIG. 7 is a top plan view, partly broken away, of a modified toe piece embodying the invention;

FIG. 8 is a longitudinal sectional view of the toe piece shown in FIG. 7 taken along a line VIII — VIII;

FIG. 9 is a longitudinal sectional view of a modified toe piece embodying the invention;

FIG. 10 is a perspective view, with the cover removed, of an assembly of the body and cam shown in FIG. 9;

FIG. 11 is a perspective bottom view of the cover utilized in the toe piece shown in FIG. 9 and

FIG. 12 is a top plan view of the cover.

DESCRIPTION OF THE PREFERRED EMBODIMENTS

With reference to the first embodiment of this invention shown in FIGS. 1 through 6, the toe piece of this invention comprises an elongated trapezoidal base plate 2 secured to a ski 1 with its longitudinal axis aligned with that of the ski. The base plate 2 is provided with an upstanding pin 3 near its fore end and an upstanding pin 4 near its rear end, the pins 3 and 4 being positioned on the center line of the base plate 2 and secured thereto by suitable fastening means such as caulkings 3a and 4a. As shown in FIG. 1, the base plate 2 is provided with openings 2a on the rear side thereof for receiving machine screws, not shown, utilized to securely fasten the base plate to the ski.

A body 5 which has a generally elongated trapezoidal shape in its top plan view is mounted on the base plate 2. The contour of the fore half of the body 5 generally conforms to that of the base plate 2, and a pair of arcuate recesses 5a are formed on both sides of the body to clear openings 2a. As best shown in FIGS. 3 and 4, the fore half of the body 5 is provided with a cam receiving chamber 6 which is defined by two side walls 6a which are parallel to the axis of the body 5, and an arcuate end wall 6b concentric with the pin 3. The fore half of

the body 5 is also formed with a circular opening 7 for receiving the pin 3. The top plate of the body 5 which closes the top opening of the cam receiving chamber 6 is provided with an arcuate slot 8 concentric with the end wall 6b, the slot 8 receiving the reduced diameter portion 4b near the upper end of the pin 4. A spring receiving opening 9 is provided to extend through the body 5 in the axial direction thereof from the fore end of the body to the fore wall 6c of the cam receiving chamber 6, and right hand screw threads 10 are formed at the outermost end portion of the opening 9.

The top portion of the body 5 is formed with a generally trapezoidal shallow recess 11 and a rectangular opening 12 communicating with the spring receiving opening 9.

A recess 5b having a generally trapezoidal configuration is formed in the rear end portion of the body 5 and a recess 13 having a square cross-sections and communicating with the recess 5b is formed along the axis of the body 5. As best shown in FIG. 5, a projection 14a of a toe clamping member 14 is received in the recess 13 and a vertical adjusting threaded rod 15 is threaded into the projection 14a with its upper and lower ends extending through the upper and lower walls of the recess 13 in a loose fitting relation thereto. Thus the toe clamping member 14 is held beneath the trailing end of the body 5 as shown in FIG. 2.

A cam 16 received in the cam receiving chamber 6 is preferably made of a self lubricating substance such as tetrafluoroethylene but other materials may of course be used. The cam 16 is provided with vertical side walls 16a slidably engaging the vertical side walls 6a of the cam receiving chamber. A spring seating recess 17 is formed through the fore end surface of the cam 16 in axial alignment with the spring receiving opening 9, and an arcuate cam surface 16b is formed at the center of the rear surface of the cam 16 for cooperating with the pin 4 in a manner to be described later. In the present embodiment, the end surfaces of the cam 16 on the opposite sides of the cam surface 16b are flat and perpendicular to the longitudinal axis of the body 5. The above described form of the cam surface is preferred because of easiness in the manufacturing thereof. The form of the cam surface is of course not strictly limited to this particular form but any workable recessed cam surface may be employed.

A compression spring 18 is inserted in the spring receiving opening 9 with its inner end sealed against the bottom of the spring seating recess 17 and its outer end abutting against a washer 20 urged by a cylindrical spring adjusting member 19 which is provided with an axial vertical slot 19a for accommodating pin 3. Right-hand screw threads 10 provided near the outer end of the spring receiving opening 9 are used to receive a screw 21 for fine adjustment. The head 22b of an adjusting screw 22 having lefthand screw threads 22a mating with the screw threads cut through the outer end wall of the spring adjusting member 19 rotatably engages the central opening of the fine adjustment screw 21. The screw 22 is provided with a flange 22c which is clamped between the outer end wall of the spring adjusting member 19 and the screw 21 for preventing withdrawal of the adjusting screw 22. The pitch of the lefthand screw threads 22a is made larger than that of the righthand screw threads of the fine adjustment screw 21. As shown in FIG. 2, a cover plate 23 is used to close the recess 11 in the upper portion of the

body 5, and the upper ends of pins 3 and 4 are interconnected by a tie plate 24 for reinforcement. A pointer, not shown, connected to the spring 18 for indicating a maximum permissible load at which the toe of the skier's boot should be released is provided to extend through the opening 12.

To use the toe piece of this invention described above, the spring adjusting member 19 is moved in the axial direction by the adjustments of the adjusting screw 22 and the fine adjustment screw 21 so as to urge the cam surface 16b of the cam 16 against the pin 4 under a suitable pressure. Under these conditions, the body 5 is positioned with its axis aligned with the longitudinal axis of the ski 1.

15 The toe clamping member 14 is adjusted in the vertical direction by turning the screw 15 for receiving the toe of the soleplate of any thickness of the skier's boot.

Due to the forward pressure applied by the heel piece, not shown, of the ski binding, the toe of the soleplate is urged into a space defined by the lower surface of the toe clamping member 14, the lower recessed surface 5b on the rear end of the body 5, and the upper surface of the ski 1 whereby the boot is firmly secured to the ski.

20 25 During the normal operation of the ski and within a predetermined range of the transverse force acting upon the skier's boot, the body 5 is caused to merely resiliently oscillate about the pin 3 in a range in which the cam surface 16b does not disengage from the pin 4 by the cooperation of the forward pressure applied by the head piece and the positioning force applied to the pin 4 by the cam surface 16b of the cam 16 under the action of the spring 18. More particularly, as long as the magnitude of the transverse force is within said predetermined range, the body 5 is pivoted about the pin 3 in the direction of the applied transverse force against the force of the spring 18. During this rotary motion of the body 5, the pin 4 is displaced laterally relative to the cam surface 16b, thus producing a restoring force.

40 45 When the transverse force disappears, the body 5 will be returned to the original position by said restoring force. In this manner, the shock applied to the ski boot can be absorbed, thus ensuring the safety of the skiing operation.

50 55 When the transverse force exceeds the maximum permissible load preset by the spring 18, the pin 4 will disengage from the recessed cam surface 16b and come into engagement with either one of the flat surfaces on the opposite sides of the cam surface 16b, thus rapidly decreasing the pressure applied to the pin 4 by the spring 18 via the cam 16. As a result, the body 5 is rotated about the pin 3 by the applied transverse force without any appreciable resistance whereby the boot is readily released from the binding thus preventing injury to the skier such as bone fractures.

60 65 As has been described hereinabove, the novel toe piece of this invention includes only one pivot point or the pin 3 and the toe clamping member 14 is not rotatable with respect to the body 5. For this reason, the defect inherent in the prior art toe piece that it becomes inoperable due to deposition of snow or ice is substantially eliminated. Moreover, if the body positioning cam 16 is made of a synthetic resinous material such as tetrafluoroethylene which has a self lubricating property at a low temperature environment, it is very easy to shape the cam surface which otherwise is required to have a complicated configuration. Moreover, it is pos-

sible to fabricate the toe piece of this invention at a low cost because it requires a relatively small number of component parts of a rugged and simple construction.

Moreover, since the spring pressure is adjusted not only coarsely by adjusting the screw 22 but also finely by the fine adjustment screw 21, it is possible to finely set any desired maximum permissible load at which the toe is released. Further, as the screw threads of these two adjusting screws are cut in the opposite direction with different pitches, there is no fear of rotating one screw which the other is being adjusted.

In a modified embodiment of this invention shown in FIGS. 7 and 8, an elongated trapezoidal base plate 31 is provided with a pair of upward projections 32 on the rear end thereof, and another pair of upward projections 33 on the side edges near the rear end, the projections 32 and 33 being respectively disposed symmetrically with respect to the longitudinal axis of the base plate 31. The base plate 31 is securely fastened to the ski, not shown, by means of screws passing through openings 34. The inner surfaces of the projections 32 are shaped to conform with a circle having a center on the center line of the base plate and a radius equal to the distance between the centers of a pivot pin 35 and of an internally threaded sleeve 33a to be described later. A body 36 pivotally mounted on the base plate 31 by means of the pivot pin 35 is formed with an arcuate slot 37 which is located to the rear of the pivot pin 35 and is concentric with the pivot pin 35. The lower end of a pressing pin 38 extending through the arcuate slot 37 is caulked to the base plate 31. A cam receiving chamber 39 is formed in the body 36 to extend in the longitudinal direction thereof, the chamber 39 being defined by vertical opposite side walls extending from the arcuate slot 37 in parallel with the longitudinal axis of the body and by the rear wall of the arcuate slot 37. A cam 40 is received in the cam receiving chamber 39 with its cam surface 40' normally urged against the pressing pin 38 by means of a compression spring 41. The cam surface 40' comprises a generally arcuate recess having its innermost portion aligned with the longitudinal axis of the body 36 and the surfaces on both sides of the cam surface 40' may be very gradually curved as shown in FIG. 7 or may be flat and perpendicular to the axis of the ski. An adjusting screw 42 is received in the threaded opening of the cam receiving chamber 39 for adjusting the pressure of the spring 41 applied to the pressing pin 38, or the safety limit.

Vertically spaced bearings 36a and 36b are provided for the rear end of the body 36 for journalling the sleeve 33. A cup shaped toe clamping member 44 is provided with a thin axial projection 44' which is rotatably mounted on the sleeve 33a between the bearings 36a and 36b of the body 36. An adjustable cup shaped member 45 is mounted on the toe clamping member 44 by means of an adjusting screw 46 received in the sleeve 33a.

A pair of vertical pins 47 extend through a pair of openings provided through the toe clamping member 44 and carry guide rollers 48 near their lower ends. The pins 47 are symmetrically disposed with respect to the longitudinal axis of the body 36. When the toe of the soleplate is held by the toe clamping member 44, or when the cam surface 40' is urged against the pressing pin 38 so as to coincide the longitudinal axis of the body 36 with that of the ski, the guide rollers 47 engage the afore-mentioned upward projections 32.

In operation, it is assumed that a transverse force is applied to the boot. Then, as the body 36 is rotated in one direction about the pin 35, and one of the guide rollers 48 is caused to disengage from the corresponding one of the projections 32 whereas the other guide roller 48 is moved away from its corresponding projection 32. Thus, the toe clamping member 44 is rotated about the sleeve 33a. As the body 36 is rotated about the pivot pin 35, the pressing pin 38 engages a different portion of the cam surface 40' thereby compressing the spring 41. The compression of the spring 41 creates a reactive force proportional to the displacement and balancing with the transverse force. When the transverse force applied to the boot disappears, the reactive force returns the body and the toe clamping member to their original positions. The resilient rotary movements of the body and the toe clamping member described above are performed while the pressing pin 38 is maintained in engagement with the arcuate cam surface 40'. In this manner, within the safety limit of the applied transverse force, the toe of the ski boot is permitted to resiliently swing about the pin 35 thus assuming a stable operation of the ski.

Should the transverse force applied to the boot, e.g. upwardly as viewed in FIG. 7, exceed the safety limit, the pressing pin 38 is caused to disengage from the arcuate cam surface 40' and comes to engage the surface on the lower side of the cam surface 40'. Then, the lower guide roller 48 will be brought to the position between the projections 32 whereas the upper guide roller 48 will be caused to roll along the surface of the upper projection 33 thus rotating the toe clamping member 44 in the counterclockwise direction. This increases the compression of the spring 41 and the reactive force of the spring acts obliquely against the pressing pin 38 whereby the pressure applied to the pressing pin 38 decreases rapidly. As a result, the body 36 can rotate freely. Thus, by the rotations of the cup shaped toe clamping member 44 and the body 36, the ski boot is released from the binding thereby protecting the skier from injury.

In another modification shown in FIGS. 9 to 12, an elongated trapezoidal base plate 51 is provided with two openings 52 for mounting it on a ski. Longitudinally spaced apart pins 53 and 54 are secured to the base plate 51 as by caulking 53a and 54a. A body 55 has a similar configuration to the base plate 51 and is provided with a rectangular cam receiving chamber 56 at its rear end, and a longitudinal spring receiving opening 57 extending between the force ends of the body and the cam receiving chamber. A cam 58 preferably made of a synthetic resinous material having self lubricating property, for example tetrafluoro ethylene, is slidably received in the cam receiving chamber 56. Although not shown in the drawing, the rear end surface of the cam 58 is provided with an arcuate recess or a cam surface which cooperates with the pivot pin 54 and the front end is provided with a spring receiving opening 59 which is coaxial with the spring receiving opening 57 to receive a compression spring 62. Screw threads 60 are cut near the outer end of the spring receiving opening 57 for receiving a spring adjusting screw 61, acting upon the spring 52 through a bottomed cylindrical member 63. For the purpose of avoiding interference with the pivot pin 53, the cylindrical member 63 is formed with a longitudinal slot

(not shown). The upper ends of pins 53 and 54 are interconnected by a tie bar 64 for reinforcement.

A cover 65 is mounted on the body 55. Referring to FIG. 11 which shows the cover 65 turned upside down, the cover 65 comprises an upper plate 67 having a recess 66 on the surface thereof, an end plate 68 and side plates 69. The end plate 68 and side plates 69 depend vertically from the upper plate 67 and cooperate to form a member having a cross-sectional configuration of a letter I. The cover 65 is provided with openings 70 and 72 for receiving pins 69 and 71, respectively, projecting upwardly from the body 55. The projecting ends of the pins 71 are caulked to fasten the cover 65. A pair of windows are formed near the opposite ends of the end plate 68 for receiving a pair of toe clamping members 73, the vertical position thereof being adjustable by means of bolts 74.

In this modification, the pressure applied to the pin 54 by the cam 56 can be adjusted by turning the adjusting screw 61, whereby the safety limit at which the toe of the soleplate is released is varied, and the vertical position of the toe clamping members 73 can be varied by turning bolts 74 so as to receive the soleplate of any thickness. By the forward pressure applied by the heel piece, not shown, the toe of the soleplate is urged into a space defined by the lower surfaces of the toe clamping members 73, the vertical wall of the end plate 68 and the upper surface of the ski, thus securing the boot to the binding.

When a transverse force less than the safety limit is applied to the boot, the body 55 is caused to merely resiliently oscillate about pivot pin 54 by the forward pressure applied by the heel piece and the pressure applied upon the pivot pin 54 by the cam 58 under the action of spring 62. Under these conditions, the cam surface of the cam 58 will not disengage from the pin 54. In other words, as long as the transverse force applied to the boot is smaller than a predetermined safety limit, the toe is held by the toe clamping members 73 and the shock can be absorbed by the swinging motion of the body 55 about the pivot pin 53.

However, when the transverse force exceeds the safety limit which is set by the adjustment of the spring 62, the pin 54 disengages the cam surface of the cam and rides on either one of the flat portions of the end surface of the cam which are located on both sides of the arcuate cam surface. Then, the pressure provided by the spring 62 is applied obliquely upon the pin 54 so that the body 55 is quickly rotated in the direction of the transverse force about the pin 53, thereby releasing the boot from the binding.

In this embodiment too, the toe piece is rotatable about only one pivot pin 53 and the toe piece clamping members 73 do not rotate with respect to the cover and the body. Moreover, the configuration of the cam is extremely simple and, since it is made of a self lubricating material such as tetrafluoroethylene, the toe piece can operate accurately even under extremely low temperature conditions.

Like the first embodiment, fine adjustment of the spring can be provided by using two adjusting screws provided with righthand and lefthand screw threads respectively. It should also be understood that two toe clamping members 73 may be combined into a single piece adjustable in the vertical direction.

What is claimed is:

1. In a toe piece of a safety ski binding of the type including a rotatable toe clamping member which acts to normally clamp the toe of the soleplate of a ski boot but is rotated to release the toe when a transverse force exceeding a predetermined limit is applied to the boot, the improvement which comprises a base plate to be secured to the ski, first and second pins which are secured to said base plate near the fore end and the rear end thereof respectively, a body pivotally mounted on said first pin located near the fore end, said body being provided with a cam receiving chamber near the rear end thereof, a cam received in said cam receiving chamber to be slidably in the direction of the axis of the ski, the rear end surface of said cam being provided with a recessed cam surface engageable with said second pin near the rear end of said base plate, a compression spring contained in said body in the axial direction thereof for normally urging said recessed cam surface against said second pin, means for adjusting the force of said spring, and a toe clamping member secured to said body at the rear end thereof, whereby when a transverse force exceeding a predetermined safety limit preset by said spring is applied to said boot, said second pin is caused to disengage from said recessed cam surface thereby to allow said cam and said body to rotate about said first pin for releasing the toe from said toe clamping member.

2. The toe piece according to claim 1 wherein said toe clamping member is provided with a forwardly projecting projection received in an opening of said body and said toe clamping member is connected to the rear end of said body by means of a bolt so as to be adjustable in the vertical direction.

3. The toe piece according to claim 1 wherein said body is provided with an arcuate slot concentric with said first pin for receiving said second pin.

4. The toe piece according to claim 1 wherein said spring adjusting means comprises a pair of cooperating adjusting members provided with oppositely directed screw threads.

5. The toe piece according to claim 1 which further includes a cylindrical member interposed between one end of said spring and said spring adjusting means and said cylindrical member is provided with a longitudinal slot for receiving said first pin.

6. The toe piece according to claim 1 which further includes means for pivotally connecting said toe clamping member to the rear end of said body, guide rollers provided on said toe clamping member and projections formed on the rear end portion of said base plate and engageable with said guide rollers for restraining rotation of said toe clamping member in a normal position of use.

7. The toe piece according to claim 1 which further includes a cover plate secured to the upper surface of said body, said cover plate having a vertical end plate which depends from the rear end thereof and has a cross-sectional configuration of a letter I, said end plate being formed with a pair of windows near both sides thereof, and a pair of toe clamping members mounted in said windows by means of bolts by which the vertical position of said toe clamping members is adjustable.

8. The toe piece according to claim 1 wherein said cam is made of a self lubricating substance.
